UNITED STATES PATENT OFFICE

125,940

DESIGN FOR A COMBINATION GASOLINE PUMP AND WINDSHIELD SERVICE CABI- NET

Lawrence V. Shepherd, Van Nuys, Calif.

Application December 3, 1940, Serial No. 97,014

Term of patent 14 years

To all whom it may concern:

Be it known that I, Lawrence V. Shepherd, a citizen of the United States and residing at 6953 Woodman Avenue, Van Nuys, Los Angeles county, California, have invented a new, original, and ornamental Design for a Combination Gasoline Pump and Windshield Service Cabinet, of which the following is a specification, reference being had to the accompanying drawing, forming part thereof.

The figure is a perspective view of a combination gasoline pump and windshield service cabinet,

showing my new design. The opposite side of the pump (not shown) is substantially the same as the side shown and the back of the pump (not shown) is substantially the same as the front shown except that a plain surface appears in the place of the windshield service cabinet in the lower half of the pump.

I claim:

The ornamental design for a combination gasoline pump and windshield service cabinet, substantially as shown and described.

LAWRENCE V. SHEPHERD.
